UNITED STATES PATENT OFFICE

MABEL McCARTY, OF PERU, INDIANA

BAG CLOSURE

Application filed November 30, 1928. Serial No. 322,923.

The present invention is directed to improvements in bag closures.

The primary object of the invention is to provide a device of this character designed particularly for closing the discharge mouth of a dust collecting bag used in connection with vacuum sweepers, the construction being such that the bag can be readily opened to remove the contents thereof.

10 Another object of the invention is to provide a device of this character so constructed that the mouth of the bag will be held firmly closed, the construction being such that no sharp corners or projections are in evidence, thereby preventing the likelihood of catching draperies or garments thereon.

Another object of the invention is to provide a device of this character which is exceedingly simple in construction, efficient in 20 operation, durable, and one which can be manufactured at a very small cost.

With these and other objects in view, this invention resides in the novel features of construction, formation, combination and 25 arrangement of parts to be hereinafter more fully described, claimed, and illustrated in the accompanying drawing, in which:—

Figure 1 is a side elevation of the bag, showing it in relative position thereof with 30 respect to the sweeper handle.

Figure 2 is a longitudinal sectional view through the bag closure.

Figure 3 is a transverse sectional view therethrough.

35 Referring to the drawing, 1 designates a conventional form of sweeper having the nozzle 2 to which is detachably connected the dust collecting bag 3, said bag being formed of suitable fabric, as customary. The closure comprises a bar 4, said bar having a longitudinal groove 5 formed therein and in which is pivotally connected one end of a rod 6, said rod being threaded, as at 7, the purpose 40 of which will be later explained.

The bar 4 is provided upon one end with an integrally connected head 8, while cooperating with the other end is an adjustable head 9, said head having a threaded bore 10 formed therein for engaging the threaded end

of the rod 6, the purpose of which will appear later.

The bar 4 is provided with an eye 11 and to which is connected the snap hook 12, said hook having a chain section 13 carried thereby. Engaged with the chain section is an eye 14 adapted to be screwed into the handle 15 of the sweeper in order to hold the closure or member 4 in proper position with respect to the handle.

It will be obvious that when the mouth or discharge end of the bag is engaged in the groove 5 the rod 6 will hold the folds thereof tightly closed, and at which time the head is rotated upon the threaded end of the rod in order that it will firmly engage the bar 4 to hold the rod 6 from accidentally disengaging the groove.

Obviously when it is desired to remove the closure it is only necessary to rotate the head 9 in a direction to disengage the end of the bar, whereupon the rod can be swung downwardly, as indicated in dotted lines in Figure 2 to permit ready removal of the bag to empty the contents therefrom when desired.

It will be observed that the heads 8 and 9 are of such formation that no sharp corners or edges are present which will prevent the same from catching or tearing the clothing of the user.

From the foregoing, it is thought that the construction, operation and many advantages of the herein described invention will be apparent to those skilled in the art, without further description, and it will be understood that various changes in the size, shape, and proportion and minor details of construction may be resorted to without departing from the spirit or sacrificing any of the advantages of the invention.

What is claimed is:—

1. A bag closure of the class described comprising a bar, a rod having one end pivotally connected to the bar, a head adjustably mounted upon the rod, said head being adapted to engage the bar to hold the rod engaged with the bag, as and for the purpose set forth.

2. A bag closure of the class described comprising a bar having a longitudinal groove

formed therein, a rod having one end pivotally connected to the bar and movable in the groove, a head threaded upon the free end of the rod for engagement with the bar to hold the rod within the groove, and in engagement with the bag.

3. A bag holder of the class described comprising a bar having a head fixed upon one end, said bar having a longitudinal groove formed therein, a rod, means for pivotally connecting the rod to the bar, said rod having a threaded end, a head engaged upon the threaded end and rotatable to engage or disengage the adjacent end of the bar, said rod serving to hold the mouth of the bag closed when the mouth of the bag is engaged in the groove.

4. A bag closure comprising a bar, said bar having a longitudinal groove formed therein, a rod having one end pivotally connected to the bar, a head adjustably mounted upon the free end of the rod, said head being adapted, when moved in one direction to engage the bar to hold the rod in the groove.

25 In testimony whereof I affix my signature.
MABEL McCARTY. [L. s.]
